UNITED STATES PATENT OFFICE.

FRANK W. KNOWLTON, OF QUINCY, MASSACHUSETTS, ASSIGNOR TO UNITED SHOE MACHINERY COMPANY, OF PATERSON, NEW JERSEY, A CORPORATION OF NEW JERSEY.

HEEL-BREAST-SCOURING MACHINE.

1,148,691.

Specification of Letters Patent.

Patented Aug. 3, 1915.

Application filed December 26, 1913. Serial No. 808,806.

To all whom it may concern:

Be it known that I, FRANK W. KNOWLTON, a citizen of the United States, residing at Quincy, in the county of Norfolk and State of Massachusetts, have invented certain Improvements in Heel-Breast-Scouring Machines, of which the following description, in connection with the accompanying drawings, is a specification, like reference characters on the drawings indicating like parts in the several figures.

This invention relates to abrading machines and is herein illustrated in connection with a machine for scouring the breasts of heels of boots and shoes.

Ordinarily a rotary wheel of conical shape is used for such work and with certain heels such a tool does not give satisfactory results. With high heeled shoes, particularly if the radius of curvature of the breast of the heel is small, it is impractical or impossible to scour that portion of the breast of the heel which is adjacent to the shank of the sole by reason of the fact that the edge of the scouring cone remote from the heel strikes the shank of the sole, thereby either preventing the edge of the scouring cone from operating upon the breast close up to the shank, or disfiguring the shank, or producing both of these undesirable results.

The object of the present invention is to produce a machine which shall be free from the disadvantages above referred to.

To this end one feature of the invention comprises a scouring tool in the form of a portion of a cylinder having an inclined end and means for oscillating said tool about the axis of the cylinder. With this construction the operator has merely to hold the breast of the heel up to the tool which, when oscillated, will reach every point in the surface of the heel breast, the shape of the tool at its inclined end preventing contact of the upper part of the tool with the shank of the sole. This and other features of the invention, including certain details of construction and combinations of parts will be described in connection with an illustrated machine and pointed out in the appended claims.

Referring now to the accompanying drawings,—

Figure 1 is a perspective of the head of a machine in which the present invention is

embodied; Fig. 2 is a front elevation of the head, and Fig. 3 is a longitudinal section showing the forward portion of the head.

Fast to a shaft 1 is a pulley 3 which may be driven from any suitable source of power 60 by means of a belt 5. A disk 7 fast to the outer end of the shaft carries a crank pin 9 upon which is loosely mounted a block 11, the said block being slidable in a guideway 13 in the tool carrier 15. The carrier is 65 mounted for angular movement about a stud 17 which is rigidly attached to the frame of the machine, said stud being provided near one end with a portion of increased diameter 19 between which and the 70 edge of a screw 21 the carrier 15 is held. The carrier is thus permitted to move angularly about the stud but is held from longitudinal movement.

Fastened about a cylindrical projection of 75 the carrier 15 by means of a split bearing and a pinch screw 23 is a scouring tool comprising a body portion 25 having the shape, except for the split bearing, of a half-cylinder. Fitted in this body portion 80 is a correspondingly shaped clamp 27 normally held spaced from the body portion 25 by springs 29 and arranged to be moved toward said body portion by a thumb screw 31. Attached to the outer side of the body 85 portion 25 is a felt backing 33 for a strip of sandpaper 35 which is drawn about it and held tightly in place by the clamp 27.

As has been stated the operative portion of the scouring tool is a segment of a cylinder. The breasting knives which determine the curvature of heel breasts have edges which are segments of circles, and for this reason the surface of the scouring tool is made to correspond to a portion of the surface of a cylinder generated by the rotation of a straight line about the axis of the stud 17.

It will be understood that tools of different sizes are provided and the one selected 100 in any given instance which corresponds to the curvature of the heel breasts which are to be scoured.

In order to permit the tool to scour the breast of the heel close up to the shank of a 105 sole the tool has a beveled or inclined end as shown in Fig. 3.

In use the shaft 1 is rotated and the shoe presented to the tool in the manner indicated in broken lines in Figs. 2 and 3. 110

Where a scouring cone is used the abrasive surface of such a cone never fits the breast of a heel and in consequence an operator, after presenting the heel to the cone, must move the shoe into different positions in order to scour the whole surface of the breast. Moreover, as has been stated above, with a certain type of shoe it is impossible to reach every portion of the breast with a scouring cone. With the device of the present invention, however, not only is it possible to reach every portion of the breast but no manipulation of the shoe is required other than to present it to the tool.

Having thus described my invention, I claim as new and desire to secure by Letters Patent of the United States:

1. A heel breast scouring machine having, in combination, a heel breast scouring tool having a curved surface the radius of which corresponds to that of the radius of curvature of the heel breast to be scoured, the end of said tool being inclined to permit it to reach into the angle at the breast of the heel with the shank of the sole, and means for oscillating said tool about its axis of curvature.

2. A heel breast scouring machine having, in combination, a heel breast scouring tool in the form of a portion of a cylinder having an inclined end, and means for oscillating said tool about the axis of the cylinder.

3. A heel breast scouring machine having, in combination, a pivot fast to the frame of the machine, a carrier mounted thereon, a heel breast scouring tool in the form of a portion of a cylinder having an inclined end mounted on said carrier, the axis of the cylinder being a continuation of the axis of the pivot, and means for oscillating the carrier.

4. A heel breast scouring tool having a body formed as a portion of a cylinder with an inclined end, a yielding backing fast to the outside of said body, a strip of abrasive material drawn about said backing, and a clamp arranged to hold the ends of said strip against the inner face of said body.

In testimony whereof I have signed my name to this specification in the presence of two subscribing witnesses.

FRANK W. KNOWLTON.
